CLAIM

The ornamental design for a triple tap electrical connector, as shown and described.

DESCRIPTION

FIG. 1 is a front perspective view showing a triple tap electrical connector according to our new design.

FIG. 2 is a rear perspective view showing the triple tap electrical connector according to our new design.

FIG. 3 is a plan view taken from the top side of the electrical connector as shown in FIG. 2, the bottom side thereof being identical.

FIG. 4 is an elevational view taken from the left side of the electrical connector shown in FIG. 3, the right side thereof being a mirror image.

FIG. 5 is an elevational view taken from the front side of the electrical connector shown in FIG. 1; and,

FIG. 6 is an elevational view taken from the rear side of the electrical connector shown in FIG. 2.

The broken lines shown in the drawings are included for the purpose of illustrating environmental structure and form no part of the claimed design.

It is certified that error appears in the above-identified patent and that said Letters Patent is hereby corrected as shown below:

Title Page should be deleted and substitute therefore the attached title page.

Drawings

Delete Figs. 1, 3, 4 and 6 and substitute therefore Figs. 1, 3, 4 and 6 as shown on the attached pages.

Signed and Sealed this

Thirteenth Day of October, 2009

David J. Kappos
Director of the United States Patent and Trademark Office
